Primary Examiner — Rhea Shields

(57) **CLAIM**

The ornamental design for a wireless charging socket, as shown and described.

DESCRIPTION

1. Wireless charging socket

1.1 : Front

1.2 : Back

1.3 : Left

1.4 : Right

1.5 : Top

1.6 : Bottom

1.7 : Perspective view 1

1.8 : Perspective view 2

The product incorporating the design is used for charging for electronic devices such as mobile phones; the drawing designated to best show the essential features of the design is the perspective view 1.
